(57) **CLAIM**

The ornamental design for a camera lens, as shown and described.

DESCRIPTION

FIG. 1 is a bottom perspective view of a camera lens showing our new design.

FIG. 2 is a top perspective view of the camera lens.

FIG. 3 is a front view of the camera lens.

FIG. 4 is a rear view of the camera lens.

FIG. 5 is a left side view of the camera lens.

FIG. 6 is a right side view of the camera lens.

FIG. 7 is a top view of the camera lens; and,

FIG. 8 is a bottom view of the camera lens.

The broken line showing of a camera lens is included for the purpose of illustrating only and forms no part of the claimed design.

1 Claim, 8 Drawing Sheets
